FISHING TACKLE ASSEMBLING AND CARRYING BAG

Stanley J. Peck and Herbert H. Lewis, both of Chesapeake, Va., assignors to Pen Dee, Incorporated, Portsmouth, Va., a corporation of Virginia

Filed Jan. 3, 1964, Ser. No. 78,046

Term of patent 14 years

(Cl. D87—5)

Fig. 1

Fig. 2

Fig. 3

Fig. 4

FIG. 1 is a front perspective view of a fishing tackle assembling and carrying bag showing our new design;

FIG. 2 is a rear perspective view thereof;

FIG. 3 is a side elevational view thereof; and

FIG. 4 is a bottom plan view thereof.

It is understood that the checkerboard pattern shown fragmentarily on the bag is continuous over its entire surface.

We claim:

The ornamental design for a fishing tackle assembling and carrying bag, as shown and described.
